INVENTOR:

Cornelius M. Brown,
BY
Russell M. Everett,
ATTORNEY.

UNITED STATES PATENT OFFICE.

CORNELIUS M. BROWN, OF NEWARK, NEW JERSEY.

MEANS FOR RETAINING FLAGS AND THE LIKE EXTENDED.

1,255,580.

Specification of Letters Patent.

Patented Feb. 5, 1918.

Application filed September 25, 1915. Serial No. 52,576.

To all whom it may concern:

Be it known that I, CORNELIUS M. BROWN, a citizen of the United States, and a resident of Newark, in the county of Essex and State 5 of New Jersey, have invented certain new and useful Improvements in Means for Retaining Flags and the like Extended, of which the following is a specification.

The objects of this invention are to provide a means separable from a flag adapted to prevent it from twisting around a supporting flag pole; to provide such a device for use more especially with substantially horizontal flag poles; to avoid injuring or 10 in any way mutilating the flag by applying the device thereto; to support the device from the flag supporting means, and thus avoid any tendency to tear the flag; to provide a construction which will not materially impair the graceful wave of the flag; 15 to utilize the design of the flag to render the device less conspicuous; to secure simplicity of construction and operation, and to obtain other advantages and results as 20 may be brought out in the following description.

Referring to the accompanying drawing, in which like numerals of reference indicate the same parts throughout the several views, 25 Figure 1 is a face view of a flag to which my device is applied;

Fig. 2 is a top edge view of the device independent of a flag;

Fig. 3 is a side edge view of the same;

Fig. 4 is a perspective view of a modified construction of my invention shown in connection with a flag, and

Fig. 5 is a face view of a further modified construction.

40 In the specific embodiment of the invention illustrated more particularly in Figs. 1, 2 and 3 of the drawing, the reference numeral 1 indicates a flag pole sloping somewhat from a horizontal position. Supported by the flag pole in any suitable manner, 45 as by a rope 2, is a flag 3, and although as shown in the drawings the rope's ends are secured to opposite sides of the flag adjacent its upper edge it will be obvious that 50 the manner in which the flag is supported by the rope or from the pole may be varied in any desired manner without departing from the spirit or scope of the invention. From the flexible nature of the usual flag 55 it is necessary to support the same from its

upper corners in order to hold it extended, and this supporting means, comprising in the present disclosure the rope in conjunction with the pole 1, extends outward from the flag at its opposite upper corners in the 60 normal plane of the flag.

My improved means for retaining flags or the like extended is carried by the supporting means of the flag, and to this end provides a pair of side members or arms 4 65 adapted to extend parallel to the side edges of the flag, preferably adjacent thereto so as to be inconspicuous, and provided at their upper ends with suitable engaging devices such as eyes 5 adapted to receive the 70 rope 2 therethrough and hang upon the same. Preferably also, the eyes 5 are large enough to be loose upon the rope, not only for greater ease in applying the same to the rope but in order to permit waving of the 75 flag in the breeze to swing the members readily and thus retain as far as possible the gracefulness of the flag as it waves. Strands of wire twisted together have been found suitable for service as the arms or 80 members 4, since the same are light, flexible, durable and economical. For ordinary purposes two strands of wire twisted together will suffice, but obviously any number desirable may be employed. Furthermore, if 85 desired the wires need not be twisted the entire length of the arms, but may be twisted adjacent the opposite ends of the arms and left untwisted the remaining length, or in fact, may be twisted in any manner found 90 desirable for the purpose. In the manufacture of the arms or side members shown herein, a wire is doubled and formed into the ring or loop 5 above described and then the two strands of the one piece of wire 95 twisted together below the ring, thus providing a permanently closed ring not liable to displacement from the supporting rope or the like.

Preferably the arms or members 4 are 100 proportioned in length substantially equal to the distance the blue union extends from the upper edge of the flag, but obviously for use with flags other than the national flag of the United States, the length of the 105 arms may be varied to more perfectly conceal the device in the design of the flag. From the lower ends of the arms or members 4 and joining the same is a transverse member for restraining the flag and cause 110

it to carry the arms with it when blowing or swinging in the breeze. For illustrative purposes this restraining member is shown as comprising two strands of wire 6, 6 slightly separated and extending in parallel relation in a plane transverse to the common plane of the arms. These strands of wire are furthermore integral, in the preferred construction, with the twisted 10 strands forming the side arms, and may therefore be in continuation of said strands. By separating the strands 6, 6 slightly, as stated, a slot 7 is formed therebetween and the flag 3 passed through the same as shown. 15 In this manner, as the flag blows from side to side it engages either one or the other of the strands and consequently swings the arms 4, 4 with the flag. The device for ordinary purposes is heavy enough to prevent 20 the flag from twisting over the pole at all, but should the end of the flag flap over, the arms will ultimately hang down vertically by gravity and the greater weight of the free end of the flag extending upward from 25 the transverse or restraining member to the flag pole will over-balance the small remaining end flapped over the pole and will accordingly cause the same to slip off the pole and the flag will then straighten out. 30 In Fig. 4 of the drawing is shown a pair of arms or members 8, 8 adapted to lie adjacent the side edges of a flag and having a connecting member 9 at their upper ends. This will serve as a rigid member for holding 35 the flag extended transversely of itself and the flag may then be carried by any support whether rigid or flexible. For illustrative purposes links 10, 10 are shown engaging the eyelets of the flag and overlying 40 a supporting member 11, said links also passing around the transverse connecting member 9 between the arms 8, 8, preferably fast thereto.

In this construction the arms are shown 45 as single strands of wire bent at their lower ends outwardly away from the flag forming hooks 12, 12, said arms or strands 8, 8 and connecting member 9 being shown as a single length or integral piece of stiff wire. 50 Extending around the arms, and prevented from falling off the same by the hooks, is a restraining member 13 comprising separated strands 14, 14, of any suitable material between which the flag 15 may be inserted. For some purposes said strands may be of rubber or other elastic material, or they may be of string, or wire, or any material found sufficient for the purpose, and said strands may be portions of one 55 continuous band of such material.

If desired a combination of the constructions shown in Figs. 1-3 and Fig. 4 may be employed, such for instance as shown

in Fig. 5, wherein a pair of arms 16 are provided having hooks 17 at their upper 65 ends adapted to receive rings or the like 18 carried by the flag supporting means. Said arms are shown as single strands of wire integrally connected at their lower ends by a connecting member 19, said arms 70 and connecting member preferably being parts of a single piece of stiff wire. Upon the arms 16, 16 adjacent the connecting member 19 are twisted the opposite ends of a finer and consequently more ductile 75 piece of wire forming a restraining member 20 the body portion of which extends between the arms substantially parallel to the connecting member 19 and adjacent thereto. A slot 21 is thus made between 80 said members 19 and 20 through which the flag may pass. Furthermore, the construction shown in this figure may be used as in the construction of Fig. 4 by the addition of a restraining member having two 85 strands such as shown in Fig. 4.

Obviously other detail modifications and changes may be made in manufacturing my improved means for retaining flags and the like extended without departing from the 90 spirit and scope of the invention, and I do not wish to be understood as restricting myself except as required by the following claims when construed in the light of the prior art. 95

Having thus described the invention, what I claim is:

1. The herein-described means for retaining flags and the like extended, comprising a pair of arms spaced apart in substantially 100 parallel relation to each other the width of a flag and providing means for retaining the same upon a flag supporting means, and a transverse restraining member connecting said arms at their ends opposite 105 from said retaining means and providing parallel and separated portions adapted to receive a flag therebetween.

2. The herein-described means for retaining flags and the like extended, comprising 110 a pair of arms spaced apart in substantially parallel relation to each other the width of a flag and providing means for retaining the same upon a flag supporting means, and a transverse restraining member 115 connecting said arms at their ends opposite from said retaining means and providing parallel and separated portions adapted to receive a flag loosely therebetween.

3. The herein-described means for retaining flags and the like extended, comprising a pair of arms spaced apart in substantially parallel relation to each other the width of a flag and having each a ring at 125 its upper end for supporting the same upon

a flag support, and means at the other ends of said arms extending between said arms adapted to retain a flag.

4. The herein-described means for retaining flags and the like extended, comprising a pair of arms spaced apart in substantially parallel relation to each other the width of a flag, each arm having a plurality of strands twisted together to form the same, and means extending between said arms adapted to retain a flag.

5. The herein-described means for retaining flags and the like extended, comprising a pair of arms spaced apart in substantially parallel relation to each other the width of a flag, said arms consisting of strands of wire twisted together with rings at corresponding ends of the arms, and means extending between said arms at their other ends adapted to retain a flag.

CORNELIUS M. BROWN.
